DESIGN FOR A PITCHER OR ARTICLE OF ANALOGOUS NATURE

Walter von Nessen, New York, N. Y., assignor to
Efcelite Corporation, a corporation of New
York

Application December 2, 1933. Serial No. 49,924

Term of patent 7 years

To all whom it may concern:

Be it known that I, WALTER VON NESSEN, a citizen of the United States of America, and a resident of New York, in the county of New York and State of New York, have invented a new, original, and ornamental Design for Pitcher or Article of Analogous Nature, of which the following is a specification, reference being had to the accompanying drawing forming a part thereof. In the drawing:

Figs. 1 and 2 are side and front elevational views respectively of the pitcher or article of analogous nature showing my new design.

I claim:

The ornamental design for a pitcher or article of analogous nature substantially as shown.

WALTER VON NESSEN.
